(57) **CLAIM**

The ornamental design for ear bud shaft and taper, as shown and described.

DESCRIPTION

FIG. 1 is a perspective view of an ear bud shaft and taper showing the new design;

FIG. 2 is a left side view thereof;

FIG. 3 is a right side view thereof;

FIG. 4 is a top view thereof;

FIG. 5 is a bottom view thereof;

FIG. 6 is a front view thereof;

FIG. 7 is a rear view thereof; and,

FIG. 8 is an illustration of an exemplary ear bud incorporating the claimed design that further includes an ear plug intended to be inserted into a user's ear.

The broken lines form no part of the claimed design.
